CONTROLLING APPARATUS FOR HIGHWAY
CROSSING SIGNALS

Howard A. Thompson, Edgewood, Pa., assignor to
The Union Switch & Signal Company, Swiss-
vale, Pa., a corporation of Pennsylvania

Application June 16, 1931, Serial No. 544,729

32 Claims. (Cl. 246—130)

My invention relates to controlling apparatus for highway crossing signals, that is, to apparatus for the control of signals which are placed at intersections of railways and highways for the purpose of warning users of the highway when a train is approaching a crossing.

One of the features of my invention is the provision of apparatus for preventing a continued operation of a highway crossing signal in the event that a train should stop within a control section for such signal before it reaches the crossing or in the event that a train having once set the signal in operation by entering the signal control section should back out of such section. Another feature of my invention is the provision of apparatus for causing a signal to be operated for approximately the same length of time when a high speed train is approaching the crossing as when a low speed train is approaching the crossing.

I will describe four forms of apparatus embodying my invention, and will then point out the novel features thereof in claims.

In the accompanying drawings, Fig. 1 is a diagrammatic view of one form of apparatus embodying my invention. Fig. 2 is a similar view of another form of apparatus embodying my invention. Fig. 3 is a similar view of still another form of apparatus constructed in accordance with the present invention. Fig. 4 is a similar view of a fourth form of apparatus constructed in accordance with the present invention.

Similar reference characters refer to similar parts in each of the several views.

Referring to the drawings, and with particular reference to Fig. 1 thereof, apparatus constructed in accordance with my invention is shown in combination with a stretch of railway track X which comprises rails 1 and 1^a and which is intersected by a highway H protected by a signal S of any preferred type. The rails 1 and 1^a are divided by insulated joints 2 to form a main section Z—G and the rail 1^a is subdivided by similar joints 3 into a series of relatively short intermediate sections Z—A, A—B, B—C, C—D and D—G. A track battery 4 is connected across the rails 1 and 1^a adjacent the right-hand end of the section Z—G, as viewed in the drawings, and a track relay R¹ is connected across the rails 1 and 1^a adjacent the left-hand end of this section. Track relays R², R³, R⁴ and R⁵ are connected in series with the relay R¹ by having the terminals of their windings connected with the rail 1^a on opposite sides of the joints 3. The apparatus also embodies a plurality of slow-releasing relays L³, L⁴ and L⁵ and a second plurality of slow-releasing relays J², J³ and J⁴,

each of which is associated with a track relay R having a corresponding exponent, and each of which controls a time element relay K which, in turn, controls the operation of the signal S.

Normally, that is to say when the section Z—G is unoccupied, the track relays R are all energized by virtue of the track circuit in which they are connected in series. The slow-releasing relays L are also all energized by virtue of circuits which receive energy from a source having terminals x and y and which include front contacts 5, 6 and 7 of the track relays R⁵, R⁴ and R³, respectively. The slow-releasing relays J are also all energized by circuits which include front contacts 8, 9 and 10 of the track relays R³, R² and R¹, respectively. Under these conditions the signal S is ineffective.

I will assume that an eastbound train proceeding toward the crossing H passes the point Z and shunts the track relay R¹, contact 10 of which will then open the pick-up circuit for relay J². I will also assume that relay J² is so constructed that if an eastbound train moves through section Z—A at a speed of, for example, not less than sixty miles per hour, the completion of a stick circuit for this relay by back contact 9 of track relay R² when the train enters section A—B will be just in time to prevent contacts 11 and 14 of relay J² from opening.

Therefore, if the train moves through section Z—A at a speed of not less than sixty miles per hour, the deenergization of relay R² when the train reaches point A will complete an operating circuit for signal S passing from terminal x, through contact 14 of relay J², contact 15 of relay R², contact 16 of relay R³, contact 19 of relay R⁴, contact 22 of relay R⁵, back contact 24 of time element relay K, and the mechanism of signal S to terminal y. Signal S, which is here indicated as a highway crossing bell, would, therefore, start ringing.

At the same time that the operating circuit is completed for signal S, time element relay K becomes energized by a circuit which follows the circuit just traced for signal S as far as contact 22 of relay R⁵, and thence passing through the winding of relay K to terminal y. Relay K is of a type which picks up slowly but releases quickly, and is designed to respond, when energized, only at the expiration of a time interval which is of sufficient duration to permit a train proceeding at a predetermined minimum rate of speed to traverse the length of any one of the sections between points A and G. The energization of relay K, as just described, will not there-

fore cause the back contact 24 of this relay to open and interrupt the signal circuit previously traced therethrough, if the train continues, without stopping, through section A—B at a rate of 5 speed not less than the minimum rate.

The opening of front contact 9 of relay R², when the train enters section A—B, breaks the pick-up circuit for relay J³ which passes from terminal x, through front contact 9, and the 10 winding of relay J³ to terminal y. I will assume that relay J³ is so constructed that if an east-bound train moves through section A—B at a speed of, for example, not less than fifty miles 15 per hour, the completion of a stick circuit for this relay by back contact 7 of track relay R³ when the train enters section B—C will be just in time to prevent contacts 12 and 17 of relay J³ from opening.

When the train enters section B—C, the deenergization of track relay R³ will open its front contact 16, thus interrupting the circuit previously traced through this contact for signal S and time element relay K. The deenergization of 20 relay R³ also causes its front contact 7 to open the circuit for the associated slow-releasing relay L³ controlled by this contact. At the expiration of a predetermined interval of time, which is 25 sufficient for relay K to become fully deenergized, relay L³ closes its back contact 18.

Therefore, if the train has moved through section A—B at a speed of not less than fifty miles 30 per hour, the deenergization of relay R³, when the train reaches point B, will complete a second operating circuit for signal S passing from terminal x, through contact 17 of relay J³, contact 18 of relay L³, contact 19 of relay R⁴, contact 22 of relay R⁵, back contact 24 of relay K, and the mechanism of signal S to terminal y. This will cause the signal S to continue its operation. The 35 signal S may be so designed that the relatively short interval, during which its operating circuit is open after the opening of contact 16 of relay R³ and before the closing of contact 18 of relay L³, will not cause a noticeable interruption in its operation. A second circuit for relay K is also 40 thus established, which causes this relay to start over again its operation for opening its contact 24.

The opening of front contact 8 of relay R³, when 45 the train enters section B—C, breaks the pick-up circuit for J⁴, which is similar to the pick-up circuit previously traced for relay J³. I will assume that relay J⁴ is so constructed that if an eastbound train moves through section B—C at a speed of, for example, not less than forty miles 50 per hour, the completion of a stick circuit for this relay by back contact 6 of track relay R⁴, when the train enters section C—D, will be just in time to prevent contacts 13 and 20 of relay J⁴ from opening. When the train enters section 55 C—D, the deenergization of track relay R⁴ will open its front contact 19, thus interrupting the circuit previously traced through this contact for signal S and time element relay K. The deenergization of relay R⁴ also causes its front contact 6 to open the circuit for the associated slow-releasing relay L⁴ controlled by this contact. At 60 the expiration of a predetermined interval of time which is sufficient for relay K to become fully deenergized, relay L⁴ will close its back contact 21.

Therefore, if the train has moved through section B—C at a speed of not less than forty miles 65 per hour, the deenergization of relay R⁴, when the train reaches point C, will complete a third operating circuit for signal S passing from ter-

5 minal x, through contact 20 of relay J⁴, contact 21 of relay L⁴, contact 22 of relay R⁵, contact 24 of relay K, and the mechanism of signal S to terminal y. This will cause signal S to continue its operation. A third circuit for relay K is also thus completed which causes this relay to start over again its operation for opening its contact 24.

When the train enters section D—G, the deenergization of track relay R⁵ will open its front contact 22, thus interrupting the circuits for signal S and time element relay K. The deenergization of relay R⁵ also causes its front contact 5 to open the circuit for the associated slow-releasing relay L⁵ controlled by this contact. At 10 the expiration of a predetermined interval of time which is sufficient for relay K to become fully deenergized, relay L⁵ will close its back contact 23, thereby completing a fourth circuit for signal S passing from terminal x, through back contact 20 15 of relay L⁵, contact 24 of relay K and the mechanism of signal S to terminal y. A fourth circuit is thereby also completed for relay K.

When the train departs from section Z—G, the track relays all become reenergized, and there- 25 upon restore the apparatus to its initial condition.

It follows that if the train proceeds uninterruptedly toward the crossing H at speeds not less than those specified for the various sections, the signal will operate except for the periodic inter- 30 ruptions between the deenergization of the relays R and the response of the associated relays L.

If the train should stop in any of the sections, the time element relay K will respond, at the 35 termination of the predetermined time interval for which it is adjusted, and open its back contact 24, thereby interrupting the signal circuit previously traced through this contact. If the train, after stopping, should go ahead and enter the next section in advance, it will deenergize the 40 track relay R associated with such section and interrupt the circuit for the relay K controlled by the front contact of such track relay. The deenergization of relay K will again cause the signal S to function as hereinbefore described. 45

If, instead of going ahead, the train should back out of section Z—G, such of the relays R as may have been deenergized will successively be reenergized in a reverse order and restore the apparatus to its normal condition without again 50 causing the signal S to function. This is because the front contacts of each relay R close before the back contact of the associated relay L opens, and consequently the relay K is maintained energized.

If, instead of proceeding through section Z—A at a speed of sixty miles per hour or higher, an eastbound train should move through this section at some lower speed, contact 11 of relay J² would open before back contact 9 of relay R² would 55 become closed. Hence, although contact 15 of relay R² would become closed in the circuits first traced for signal S and relay K, these circuits would still be open at contact 14 of relay J². Hence signal S would not be operated before the 60 train arrived at point B.

If the train should proceed through section A—B at a speed of fifty miles per hour or higher, signal S and relay K would become energized by the second circuit which was traced through contact 17 of relay J³ and contact 18 of relay L³. If, however, the train proceeded through section A—B at a speed of less than fifty miles per hour, contact 12 of relay J³ would open before back contact 7 of relay R³ would close. Hence contact 75

17 of relay J³ would also open, and would therefore prevent operation of signal S and energization of relay K, although back contact 18 of relay L³ were closed.

5 If the train should now proceed through section B—C at a speed of forty miles per hour or higher, signal S and relay K would become operated by the third circuit traced through contact 20 of relay J⁴ and contact 21 of relay L⁴. If, 10 however, the train proceeded through section B—C at a speed of less than forty miles per hour, contact 13 of relay J⁴ would open before back contact 6 of relay R⁴ would become closed. Contact 20 of relay J⁴ would therefore also be 15 opened and prevent operation of signal S and relay K, although back contact 21 of relay L⁴ were closed.

20 Signal S will, however, be operated for a given period every time relay L⁵ becomes deenergized on account of the presence of a train in section D—G, or when relay L⁵ becomes deenergized for any other reason.

25 Sections Z—A, A—B and B—C may be of equal lengths, while relays J², J³ and J⁴ may be constructed to have different periods of release according to the minimum train speeds of sixty, fifty and forty miles per hour, respectively. A modification of this arrangement could provide relays J², J³ and J⁴ with equal periods of release, 30 but with the lengths of sections Z—A, A—B and B—C varied according to the minimum train speeds of sixty, fifty and forty miles per hour, respectively.

35 The speed of a train moving through sections Z—A, A—B and B—C determines whether or not bell S shall ring when the train reaches points A, B and C, respectively. The speed of a train moving through section C—D does not, however, determine whether or not bell S shall ring when 40 the train reaches point D. Bell S will ring whenever an eastbound train enters section D—G.

45 In the forms of apparatus shown in Figs. 2, 3 and 4, there is no means controlled by the speed of a train in one section for determining whether or not the bell will ring when the train enters the next section in advance as in Fig. 1. In the 50 forms of apparatus shown in Figs. 2, 3 and 4, the bell will ring when a train enters each section, and will continue to ring while the train is in each section unless the train stops or is moving at less than a given minimum speed which, for example, might be fifteen miles per hour. The train speed at which the bell will stop ringing is determined by the time required 55 for slow pick-up relays P of Figs. 2 and 3 and relay W of Fig. 4 to open their back contacts.

60 With the forms of apparatus shown in Figs. 2 and 3, sections A—B, B—C, C—D, D—E and E—F may be of equal lengths. Section F—G should preferably be short.

65 With each of the four forms of apparatus shown, the bell will stop ringing if a train remains in a section long enough for a slow pick-up relay, such as relay K of Fig. 1, relay P of Figs. 2 and 3, and relay W of Fig. 4, to open its back contact.

70 In Fig. 2, I have shown another form of apparatus constructed in accordance with my invention. In this particular construction, I employ a series of transformers T designated by appropriate exponents, and having primary and secondary windings *a* and *b*, respectively. The primary *a* of transformer T¹ is connected in series with the track relay R¹, and the secondary *b* of 75 transformer T¹ is connected with the movable

control winding 25 of a galvanometer relay M through flexible connections 25^a and 25^b. This relay comprises a core *d* provided with a stationary winding 26 which is constantly energized by a battery 21. The terminals of the primary winding of each of the transformers T², T³, T⁴, T⁵ and T⁶ are connected with the rail *1a* on opposite sides of the insulated joints 3, and the secondaries of these transformers are connected in parallel with each other and with winding *b* 10 of transformer T¹. The apparatus also includes two neutral relays N¹ and N² and a slow acting relay P which, as here shown, is of the type which releases quickly and picks up slowly. Under normal conditions, the track relay R¹ is 15 energized by its track circuit but winding 25 of the galvanometer relay M, the neutral relays N¹ and N² and the time element relay P are all deenergized.

20 With the apparatus in this condition, I will assume that an eastbound train, approaching the crossing H, enters section A—G at A and causes the deenergization of track relay R¹. This will complete a circuit passing from terminal *x* of a source of electric energy not shown in the drawings, through back contact 28 of track relay R¹, back contact 29 of time element relay P, and operating mechanism of signal S to terminal *y* of the same source. This will cause the signal to operate and warn traffic on the highway H of the 25 approach of the train. The train, as well as shunting track relay R¹, also shunts the primary *a* of transformer T¹. The dying down of the current in this primary *a* causes a momentary surge of current to be induced in the secondary *b* 30 of the same transformer, flowing from left to right as shown in the drawings and of sufficient magnitude to energize the movable control winding 25 of the galvanometer relay M momentarily. This completes a pick-up circuit for relay N² passing from terminal *x*, through back contact 28 of track relay R¹, front contact 30 of relay M, back contact 31 of slow pick-up relay P, back contact 32 of neutral relay N¹, and winding of neutral 35 relay N² to terminal *y*. This causes relay N² to 40 close its front contact 33.

45 As soon as the surge of current in the winding 25 of the galvanometer relay M dies out, front contact 30 of this relay opens and interrupts the pick-up circuit just traced for relay N². However, immediately upon the opening of front contact 30 of relay M and before back contact 34 of this relay has had time to close, a pick-up circuit for relay N¹ and a holding circuit for relay N² is established passing from terminal *x* through back contact 28 of track relay R¹, front contact 33 of relay N², and the windings of relays N¹ and N² in series to terminal *y*. As soon as back contact 34 of relay M closes, a second pick-up circuit 50 is established for relay N¹ passing from terminal *x*, through back contact 28 of relay R¹, front contact 33 of relay N², winding of relay N¹, and back contact 34 of relay M to terminal *y*. Both terminals of the winding of relay N² are now 55 connected with terminal *y* with the result that relay N² is shunted and so rendered slow-releasing. This delays the opening of front contact 33 of relay N² for a time interval of sufficient duration to permit front contact 35 of relay N¹ to close. 60 The closing of front contact 35 of relay N¹ completes a stick circuit for this relay passing from terminal *x*, through back contact 28 of relay R¹, back contact 30 of relay M, front contact 35 of relay N¹, winding of relay N¹, and back contact 65

70 75

34 of relay M to terminal y. The energization of relay N¹ establishes a circuit for the time element relay P passing from terminal x, through back contact 28 of track relay R¹, front contact 36 of relay N¹, and winding of relay P to terminal y, but relay P being slow acting, does not respond until a predetermined time interval has elapsed of a duration sufficient to allow a train, moving at a certain minimum speed, fifteen miles per hour 10 for example, to enter section B—C.

When the train enters section B—C, the transformer T² is shunted which causes the galvanometer relay M to become energized again momentarily, as hereinabove described, and to open its back contact 30. This interrupts the stick circuit for relay N¹, previously traced through this contact, thereby causing the deenergization of this relay. The deenergization of relay N¹ causes its front contact 36 to open, thus interrupting the circuit for relay P long enough to permit this relay, which is of the type that releases quickly, to become fully deenergized. The deenergization of relay N¹ also causes back contact 32 thereof to close and consequently when relay M closes its front contact 30, the circuit for relay N², previously traced through these contacts, is completed. From this point on, the cycle of operations hereinbefore described is repeated.

I will now assume that a train has entered one of the sections between the points A and G and also that the relay N¹ is energized by its stick circuit previously traced and that the time element relay P is energized by virtue of its pick-up circuit but has not yet responded. Under these conditions, if the train should stop, the time element relay P will, at the expiration of the time interval for which it is adjusted, respond and open its back contact 29. This will interrupt the circuit previously traced through this contact for the signal S and cause it to discontinue its operation. If the train should now proceed into the next section toward G, it will shunt the transformer T for such section and will thus cause the energization of the galvanometer relay M which 45 will open its back contact 30 and interrupt the stick circuit for relay N¹. This will cause relay N¹ to open its front contact 36 and interrupt the circuit for time element relay P which will again close its back contact 29 and reestablish the circuit for the signal S.

On the other hand, if the train, instead of proceeding, should back out of the main section A—G, it will successively permit the reenergization of such of the transformers T as may have 55 been shunted thereby. The reenergization of any of the transformers, however, will tend to cause a surge of current in the circuit for the galvanometer relay M of an opposite polarity such as will tend to maintain the back contacts of relay M closed. As a result, the stick circuit for relay N¹ is not opened and the circuit for the time element relay P previously traced through front contact 36 of relay N¹ is maintained intact. The signal circuit through back contact 29 of relay P 60 therefore remains open. It may be desirable to connect an asymmetric unit r in series with the secondary of each of the transformers T so as to prevent the surge of current produced in the secondary b of any one of the transformers, caused 65 by the shunting of its primary by a train, from dissipating itself in the secondary of another of the transformers, the primary of which has been and still is shunted by the same train.

Asymmetric units r, arranged as shown, will 75 also prevent surges of current in the reverse

direction, from right to left, from forcing the contacts of relay M against their back points when a train backs away from crossing H.

It will be apparent from the foregoing that as long as a train proceeds uninterruptedly through the several sections at a speed not less than a predetermined minimum, the signal S will operate without interruption, but that if the train should stop or back out of signal control territory the operation of the signal will discontinue. In this respect the apparatus functions as an indication of the progress of a train approaching the crossing H.

In Fig. 3, I have shown another form of apparatus constructed in accordance with my invention 15 in which I employ a polarized relay Q instead of the galvanometer relay M shown in Fig. 2. In this embodiment of my invention, if a train enters section A—B, it will deenergize the track relay R¹ and cause it to close its back contact 28, thus 20 establishing the signal circuit previously traced. The train upon entering section A—B also shunts the primary of the transformer T¹ and causes a momentary energization of the polar relay Q. This causes front neutral contact 37 of relay Q to 25 close and establish a pick-up circuit for relay N² passing from terminal x, through back contact 28 of track relay R¹, front neutral contact 37 and normal polar contact 38 of relay Q, back contact 31 of time element relay P, back contact 32 of 30 relay N¹, and winding of relay N² to terminal y. The energization of relay N² causes it to close its front contact 33. As soon as the surge of current in the circuit for relay Q dies out, front contact 37 of relay Q opens and interrupts the circuit 35 just traced through this contact for relay N², but a pick-up circuit for relay N¹ is established, in series with relay N², passing from terminal x, through back contact 28 of track relay R¹, front contact 33 of relay N², and windings of relays 40 N¹ and N² to terminal y.

As soon as relay Q closes its back contact 39, a second pick-up circuit is established for relay N¹ passing from terminal x, through back contact 28 of relay R¹, front contact 33 of relay N², winding of relay N¹, and back contact 39 of relay Q 45 to terminal y. Both terminals of the winding of relay N² are now connected with terminal y with the result that relay N² is shunted and rendered slow-releasing. This delays the opening of front contact 33 of relay N² for a time interval of sufficient duration to permit front contact 35 of relay N¹ to close. The closing of this contact establishes a stick circuit for relay N¹ passing from terminal x, through back contact 28 of track 50 relay R¹, back neutral contact 37 of polar relay Q, front contact 35 of relay N¹, and back neutral contact 39 of polar relay Q to terminal y. The energization of relay N¹ also causes front contact 36 of this relay to close and establish a circuit 55 for time element relay P passing from terminal x, through back contact 28 of track relay R¹, front contact 36 of relay N¹, and winding of relay P to terminal y. If the train proceeds at a speed not less than the predetermined minimum, previously referred to, it will enter section B—C before the time element relay P opens its back contact 29 60 in the circuit for signal S controlled thereby.

When the train enters section B—C, the transformer T² is shunted which causes the polar relay Q to become energized again momentarily, as hereinabove described, and open its back contact 37. This interrupts the stick circuit for relay N¹, previously traced through this contact, thereby causing the deenergization of this relay. 75

The deenergization of relay N^1 causes its front contact 36 to open, thus interrupting the circuit for relay P long enough to permit this relay, which is also of the type that releases quickly, 5 to become fully deenergized. The deenergization of relay N^1 also causes back contact 32 thereof to close and consequently when relay Q closes its front contact 37 the circuit for relay N^2 , previously traced through these contacts, is completed. 10 From this point on, the cycle of operations hereinbefore described in connection with this particular form of my invention is repeated.

If the train should back out of any one of the 15 sections, it will permit the reenergization of the transformer for that section and will so tend to cause a surge of current in the circuit for the polar relay Q . The surge of current in such case, however, will be of opposite polarity to that caused by the shunting of the transformer and 20 therefore this relay will open its normal polar contact 38 and close its reverse polar contact 40. This establishes a branch path for the stick circuit for relay N^1 through reverse polar contact 40 of relay Q and thus maintains relay N^1 energized and the circuit for relay P through front contact 36 of relay N^1 intact, notwithstanding that back normal contact 37 which controls the main path for the stick circuit for relay N^1 is subsequently opened. The time element relay P 25 is thus maintained energized and the signal circuit through its back contact 29 held open during the backing movement of the train.

It may be desirable to connect an asymmetric unit r in series with the secondary winding of 30 each of the transformers T in order to prevent the current generated in any one of these secondaries from being dissipated in the other secondaries. Asymmetric units r , if used, will also prevent surges of current in the reverse direction 35 from energizing relay Q .

In Fig. 4, I have shown apparatus constructed in accordance with a still further embodiment of my invention in which I employ an ammeter relay U , two neutral relays V^1 and V^2 and a time element relay W , which as here shown has a slow pick-up and a quick release, for controlling the signal S , and in which the track X is divided by insulated joints 2 to form a single unbroken section $A-G$ extending the entire length of the signal control territory. The relay U comprises the usual movable coil 41 the opposite terminals of which are connected with terminal posts 42 and 43 by means of flexible connections 43^b and 43^a, respectively, and which is mounted for oscillatory 45 movement between the pole pieces 44 of a permanent magnet 45. The coil 41 actuates an arm 46 one end of which is connected by a flexible connection 47 with a terminal post 48 and the other end of which carries a contact 49 for engagement with a contact 50 which is connected by a flexible connection 51 with a terminal post 52. The contact 50 is carried by a slide 53 mounted in a guideway 54 so that when the coil 41 is energized, the arm 46 will first carry the contact 49 into engagement with the contact 50 and then as the current increases, will move the contact and slide bodily in a clockwise direction, as viewed in the drawings. When the current in the coil 41 is interrupted, the arm 46 first carries the 55 contact 49 out of engagement with the contact 50 and then engages a shoulder 55 on the slide 53 and returns the slide and contact 50 to their initial positions. The terminal post 42 of the coil 41 is connected directly with the rail 1^a of the track X adjacent the point G , and the other

terminal 43 of this coil is connected with one terminal of a battery 56, the other terminal of which is connected through a resistor 57 with the rail 1 of the track X adjacent the point G .

In this apparatus, if an eastbound train enters section $A-G$, a circuit for coil 41 will be completed, passing from one terminal of battery 56, through resistor 57, rail 1, wheels and axles of the train, rail 1^a, terminal post 42, coil 41, and terminal post 43 to the other terminal of battery 56. This will cause the arm 46 to swing in a clockwise direction and move the contact 49 carried thereby into engagement with the contact 50. This will cause the signal S to operate by virtue of a circuit passing from a battery 58, 15 through terminal post 48, flexible connection 47, arm 46, contacts 49-50, flexible connection 51, terminal post 52, back contact 59 of time element relay W , and operating mechanism of signal S to battery 58. A circuit is also established, 20 passing from battery 58, through arm 46 and contacts 49-50 of relay U , back contact 60 of relay V^2 , and winding of relay V^1 to battery 58. The energization of relay V^1 shunts the left-hand portion of the resistor 57 by establishing 25 a circuit passing from battery 56, through front contact 61 of relay V^1 , right-hand portion of resistor 57, rail 1, wheels and axles of the train, rail 1^a and coil 41 of ammeter relay U to battery 56. This increases the current flowing in coil 41 30 and causes the arm 46 and contacts 49-50 to move forward a certain distance. The energization of relay V^2 also causes the energization of relay V^1 by virtue of a pick-up circuit passing from battery 58, through front contact 62 of 35 relay V^1 , and winding of relay V^2 to battery 58. This causes relay V^2 to close its front contact 63 which establishes a stick circuit for this relay, passing from battery 58, through back contact 64 of time element relay W , front contact 63 of 40 relay V^2 and winding of this relay to battery 58. The energization of relay V^2 causes it to open its back contact 60 and interrupt the circuit previously traced through this contact for relay V^1 . This causes relay V^1 to open its front contact 45 61 and to interrupt the circuit previously traced through this contact which shunted the left-hand position of the resistor 57, thereby increasing the resistance to the current flow in the coil 41 and causing the arm 46 to move to the left 50 and open contacts 49-50. This does not, however, interfere with the operation of the signal S for the reason that a circuit is now established for the signal passing from battery 58, through front contact 60 of relay V^2 , back contact 59 of 55 time element relay W , and operating mechanism for signal S to battery 58. The energization of relay V^2 also causes it to close its front contact 65 which establishes a pick-up circuit for time element relay W , but this relay, being 60 adjusted to operate only after a predetermined time interval has elapsed, does not immediately respond.

Now if the train proceeds at a speed not less than a predetermined minimum, it will decrease 65 the resistance of the circuit including rails 1 and 1^a for the coil 41 so that the arm 46 will again move to the right and close the signal circuit through contacts 49-50 before the time element relay W functions. The time element relay W 70 afterward responds and opens its back contacts 59 and 64, thereby interrupting the circuit for signal S and the stick circuit for relay V^2 , respectively, previously traced through these contacts. The deenergization of relay V^2 immediate- 75

ly opens its front contact 65, thus interrupting the circuit for the time element relay W and causing this relay to close its back contact 59 which again causes the operation of signal S. 5 The interval of time during which the circuit for signal S is thus interrupted is only that required for the front contact 65 of relay V² to open and the back contact 59 of relay W to close. The deenergization of relay V² also closes its back 10 contact 60, thereby reestablishing the circuit for relay V¹ previously traced. The apparatus is thus restored to its initial condition and the cycle of operations above described is repeated.

It will be noticed that if the train proceeds at 15 not less than a given minimum speed, the operation of signal S is not interrupted when the signal circuit through the contacts 49-50 is opened on account of the opening of contact 61 of relay V¹, a second circuit for the signal being 20 then established through back contact 59 of time element relay W and front contact 60 of relay V². The design of the signal S may be such that its operation will be continuous notwithstanding the periodic brief interruptions in its 25 operating circuits by relay W. If, however, the train should stop anywhere within section A-B, the contacts 49-50 will not close, and therefore when the time element relay W responds and opens its back contact 59, the branch path controlled by front contact 60 remains open and the signal S will cease operation. If the train should proceed after stopping, the decreased resistance in the circuit for coil 41 will again cause the contacts 49-50 to close and reestablish the circuit 30 for signal S.

Although I have herein shown and described only four forms of apparatus embodying my invention, it is understood that various changes and modifications may be made therein within 40 the scope of the appended claims without departing from the spirit and scope of my invention.

Having thus described my invention, what I claim is:

1. In combination, a stretch of railway track 45 intersected by a highway, a signal for controlling traffic on said highway at such intersection, a time element relay for controlling said signal, and means controlled by a train proceeding uninterruptedly over said stretch for successively forestalling operation of said time element relay.

2. In combination, a stretch of railway track intersected by a highway, a signal for governing traffic over said highway at such intersection, a slow-acting relay for controlling the operation of 55 said signal, a track relay for controlling the operation of said slow-acting relay, and means operable by a train at varying distances from such intersection for periodically controlling the operation of said slow-acting relay independently of said track relay.

3. In combination, a stretch of railway track intersected by a highway, a signal for governing traffic over said highway at such intersection, a slow-acting relay for controlling the operation 65 of said signal, a track relay operable by a train upon entering said stretch for starting the operation of said slow-acting relay, and means operable by a train at predetermined time intervals for stopping and restarting the operation of said slow-acting relay.

4. In combination, a stretch of railway track intersected by a highway, a signal for controlling traffic on said highway at such intersection, a slow-acting relay for controlling said signal, 70 means operable by a train at different locations

in said stretch for energizing said slow-acting relay, and means controlled by said train operable means for causing the deenergization of said slow-acting relay.

5. In combination, a stretch of railway track 5 intersected by a highway, a signal for controlling traffic on said highway at such intersection, a time element relay for controlling said signal, and means operable by a train at different points along said stretch for alternately rendering said time element relay effective and ineffective. 10

6. In combination, a stretch of railway track intersected by a highway, a signal for controlling traffic on said highway at such intersection, a time element relay for controlling said signal, 15 and means operable by a train at time intervals of predetermined duration for alternately causing the energization and deenergization of said time element relay.

7. In combination, a stretch of railway track 20 intersected by a highway, a signal for controlling traffic on said highway at such intersection, a time element relay for controlling said signal, means operable by a train upon entering said stretch for causing the energization of said time 25 element relay, and means operable by such train at predetermined distances from said intersection for successively causing the deenergization of said time element relay momentarily.

8. In combination, a stretch of railway track 30 intersected by a highway, a signal for controlling traffic on said highway at such intersection, a time element relay for controlling said signal, a circuit for said time element relay, and means operable by a train at different points in said 35 stretch for successively interrupting said circuit.

9. In combination, a stretch of railway track divided into a plurality of sections, a signal, a time element relay for controlling said signal, a circuit for said time element relay, and means 40 associated with each of said sections for interrupting said circuit momentarily.

10. In combination, a stretch of railway track divided into a plurality of sections, a signal, a time element relay for controlling said signal, 45 and means associated with each of said sections for periodically delaying the operation of said relay.

11. In combination, a stretch of railway track divided into a plurality of sections, a signal, a time element relay for controlling said signal, 50 a contact device associated with each of said sections, a plurality of control relays controlled by said contact devices, a main circuit for said time element relay controlled by each of said contact 55 devices, and a plurality of auxiliary circuits for said time element relay, each controlled by one of said control relays.

12. In combination, a stretch of railway track divided into a plurality of sections, a plurality of 60 track relays connected in series and adapted to be successively deenergized by a train proceeding through said sections, a plurality of auxiliary relays each controlled by one of said track relays, a signal, a time element relay, a circuit for said time 65 element relay controlled by each of said track relays, a circuit for said signal controlled by each of said track relays and by said time element relay, and a plurality of additional circuits for said signal each controlled by said time element 70 relay and by one of said auxiliary relays.

13. In combination, a stretch of railway track divided into a plurality of sections, a signal, a time element relay for controlling said signal, a track relay associated with each of said sections, 75

- a circuit for said time element relay including distances from said intersection for successively a front contact of each of said track relays, and energizing said control relay.
21. In combination, a stretch of railway track auxiliary relay associated with each of said track relays; a circuit for each of said auxiliary relays including a front contact of the associated track relay, and a plurality of auxiliary circuits for said time element relay each controlled by a back contact of one of said auxiliary relays.
14. In combination, a stretch of railway track divided into a plurality of sections; a signal, a time element relay for controlling said signal, a circuit for said time element relay, a track relay associated with each of said sections for controlling said circuit, and a relay controlled by each of said track relays for controlling said circuit jointly with the associated track relay.
15. In combination, a stretch of railway track divided into a plurality of sections; a signal, a time element relay for controlling said signal, a track relay associated with each of said sections for controlling said time element relay, and a plurality of slow-releasing relays each controlled by one of said track relays for controlling said signal jointly with said track relays.
25. 16. In combination, a stretch of railway track intersected by a highway, a signal for controlling traffic over said highway at such intersection, a plurality of track relays arranged at intervals along said track, a slow pick-up relay, a circuit for said signal including a front contact of each of said track relays and a back contact of said slow pick-up relay, and a circuit for said slow pick-up relay including said front contacts of said track relays.
35. 17. In combination, a stretch of railway track intersected by a highway, a signal for controlling traffic over said highway at such intersection, a plurality of track relays arranged at intervals along said track, a slow pick-up relay, a plurality of slow-releasing relays, a first circuit for said signal controlled by said track relays and by said slow pick-up relay, and a plurality of additional circuits for said signal each controlled by certain of said track relays and by one of said slow-releasing relays.
45. 18. In combination, a stretch of railway track intersected by a highway, a signal for controlling traffic over said highway at such intersection, a plurality of track relays arranged at intervals along said track, an auxiliary relay associated with certain of said track relays, and a slow-acting relay controlled by said track relays and by said auxiliary relays for controlling said signal.
55. 19. In combination, a stretch of railway track intersected by a highway, a signal for governing traffic over said highway at such intersection, a slow-acting relay for controlling said signal, an auxiliary relay for controlling said slow-acting relay, a control relay, a pick-up circuit for said auxiliary relay controlled by said control relay, a stick circuit for said control relay, and means controlled by a train at varying distances from said intersection for successively energizing said control relay.
65. 20. In combination, a stretch of railway track intersected by a highway, a signal for governing traffic over said highway at such intersection, a slow-acting relay and a track relay for jointly controlling said signal, an auxiliary relay for controlling said slow-acting relay, a control relay, a pick-up circuit for said auxiliary relay controlled by said control relay, a stick circuit for said auxiliary relay controlled by said control relay, and means controlled by a train at varying
21. In combination, a stretch of railway track intersected by a highway, a signal for governing traffic over said highway at such intersection, a slow-acting relay and a track relay for jointly controlling said signal, an auxiliary relay for controlling said slow-acting relay, a control relay, a pick-up circuit for said auxiliary relay controlled by said control relay, a stick circuit for said auxiliary relay controlled by said control relay, and a plurality of track transformers arranged at varying distances from said intersection for successively energizing said control relay.
22. In combination, a stretch of railway track intersected by a highway, a signal for governing traffic over said highway at such intersection, a slow-acting relay for controlling said signal, an auxiliary relay for controlling said slow-acting relay, a polar relay, a pick-up circuit for said auxiliary relay controlled by said polar relay, a stick circuit for said auxiliary relay controlled by said polar relay, and means controlled by a train at varying distances from said intersection for successively energizing said polar relay.
30. 23. In combination, a stretch of railway track intersected by a highway, a signal for governing traffic over said highway at such intersection, a slow-acting relay for controlling said signal, a first auxiliary relay for controlling said slow-acting relay, a second auxiliary relay, a control relay, a pick-up circuit for said second auxiliary relay controlled by said control relay, a pick-up circuit for said first auxiliary relay controlled by said second auxiliary relay, a stick circuit for said first auxiliary relay controlled by said control relay, and means controlled by a train at varying distances from said intersection for successively energizing said control relay.
40. 24. In combination, a stretch of railway track intersected by a highway, a signal for governing traffic over said highway at such intersection, a slow-acting relay for controlling said signal, a first auxiliary relay, a second auxiliary relay for controlling said slow-acting relay, a polar relay, a pick-up circuit for said second auxiliary relay controlled by a front neutral contact and a normal polar contact of said polar relay, a pick-up circuit for said first auxiliary relay controlled by a front contact of said second auxiliary relay, a first stick circuit for said first auxiliary relay controlled by a back neutral contact of said polar relay, a second stick circuit for said first auxiliary relay controlled by a reverse polar contact of said polar relay, and means controlled by a train at varying distances from said intersection for successively energizing said polar relay in a normal direction when said train is approaching said intersection and for successively energizing said polar relay in a reverse direction when said train is backing away from said intersection.
50. 25. In combination, a stretch of railway track intersected by a highway, a signal for governing traffic over said highway at such intersection, a control relay controlled by a train in said stretch for controlling said signal, a slow-acting relay for controlling said signal jointly with said control relay, a first auxiliary relay for controlling said slow-acting relay, a second auxiliary relay, a pick-up circuit for said second auxiliary relay controlled by said control relay and by said first auxiliary relay, a pick-up circuit for said first auxiliary relay controlled by said second auxiliary relay, a stick circuit for said first auxiliary relay controlled by said slow-acting relay, and means

controlled by said second auxiliary relay for controlling said control relay jointly with said train.

26. In combination, an electrical conductor, an indication device, means for supplying current to said conductor, means for energizing said indication device when the current in said conductor increases, and means for alternately energizing and deenergizing said indication device when said current ceases to increase faster than a given rate and for again energizing said device constantly when said current again increases.

27. In combination, a stretch of railway track intersected by a highway, a highway crossing signal for said intersection, a slow-release relay responsive to the speed of a train approaching said intersection so that it remains closed if a train approaches at high speed but becomes open if a train approaches at a lower speed, means controlled by said relay for operating said signal when a train moving at high speed arrives at a given point, and means for starting operation of said signal when a train moving at a lower speed arrives at a point nearer said intersection.

28. In combination, a stretch of railway track intersected by a highway, a highway crossing signal for said intersection, a plurality of slow-release relays responsive to the speed of a train approaching said intersection, and means controlled by each of said relays for operating said signal when a train arrives at a corresponding distance from said intersection.

29. In combination, a stretch of railway track intersected by a highway, a highway crossing signal for said intersection, a stick relay having a pick-up circuit which becomes opened when a train arrives at a given point and having a stick circuit which becomes closed if a train approaching said intersection arrives at a second point within a given period of time after arriving at said first point, and means controlled by said relay for controlling said signal.

30. In combination, a section of railway track including an insulated joint in one rail, a signal adjacent one end of said section, a track circuit

for said section including a battery connected across the rails at one end of the section and a relay connected across the rails at the opposite end of said section as well as a second relay connected to the one rail around said insulated joint, a slow-release stick relay, a pick-up circuit for said stick relay including a front contact of said first relay, a stick circuit for said stick relay including a back contact of said second relay, and a circuit including a front contact of said stick relay for controlling said signal.

31. In combination, a stretch of railway track one rail of which is divided by insulated joints into a plurality of successive sections, a plurality of transformers the primary winding of each of which is connected to said rail around a corresponding one of said insulated joints, a track circuit for said stretch including a track battery connected across the rails adjacent one end of said stretch and a track relay connected across the rails adjacent the other end of said stretch, an electrical device, a circuit comprising a plurality of branch paths each of which includes a secondary winding of one of said transformers and which are in multiple with each other but 25 in series with said electrical device, and a plurality of asymmetric units each of which is connected in a corresponding one of said branch paths to prevent current generated in each of said secondary windings from being dissipated in any 30 of the other secondary windings.

32. In combination, a section of railway track, a source of current connected across the rails of the track adjacent one end of said section, a highway crossing signal, and means for causing operation of said signal when the magnitude of the current drawn from said source is increasing due to the shunting action of a train approaching the said end of the section and for stopping the operation of said signal when the 40 magnitude of such current ceases to increase due to the stopping of such train in the section.

HOWARD A. THOMPSON.
